SIGNAL OR INDICATING DEVICE

Robert Ladue, Minneapolis, Minn.

Application September 12, 1938, Serial No. 229,538

4 Claims. (Cl. 177—311)

This invention relates to a signal or to an indicating device. While the invention may have various applications and uses, in the embodiment of the same illustrated it is constructed and arranged to be connected to and operated by a cash register. It is a custom in many places to remit the price of a purchase or to make no charge for the purchase when an indicator assumes a certain position. One form of such indicator comprises a device having a dial with a hand movable thereover and cooperating with circumferentially spaced indications on the dial. Each time the cash register is operated to record a purchase or a sale the indicating device is operated so that the hand is spun and comes to rest in registry with one of said indications. When the hand comes to rest in registry with some certain indication a signal is sounded or operated and the customer is not charged for the goods.

It is an object of this invention to provide a simple and efficient signal or indicating device which can be operated by the closing of a pair of electrical contacts which will sound or operate a signal upon certain conditions.

It is a further object of the invention to provide a signal or indicating device comprising a dial having a hand movable thereover and adapted to register with indications on the dial together with means rotatable with said hand adapted to close an electrical circuit and operate a signal when said hand stops in a certain position.

These and other and more specific objects and advantages of the invention will be fully set forth in the following description made in connection with the accompanying drawing in which like reference characters refer to similar parts throughout the several views and in which:

Fig. 1 is a view in front elevation of said device;

Fig. 2 is a vertical section taken on line 2—2 of Fig. 1 as indicated by the arrows;

Fig. 3 is a view in rear elevation, certain parts being broken away; and

Fig. 4 is a partial view similar to Fig. 3 showing the parts in different positions.

Referring to the drawing a device is shown comprising a dial 10. While this dial may have various shapes in the embodiment of the invention illustrated it is shown as made of a rectangular piece of sheet material. While the dial could be made of metal or other suitable material, in practice it has usually been made of glass. A frame member 11 is provided having a flat rectangular face portion forming the support for the device and having an upstanding lip 11a disposed at and engaging the lower front portion of dial 10

into which said dial may be secured. A cylindrical casing 12 is disposed in the rear of dial 10 and secured to arms 11b of frame member 11 which extend upwardly towards each other and have portions 11c engaging casing 12 and secured thereto in any suitable manner as by welding. The removable cover 13 is provided for the rear end of casing 12 having a flange 13a fitting over the rear end of said casing and secured thereto by circumferentially spaced screws 14. A bracket 15 has a portion secured to the top of casing 12 by headed and nutted bolts 16, said bracket engaging the rear side of dial 10 at its upper central portion and being reversely bent to extend down along the front of said dial. Bracket 15 is again reversely bent upwardly and has a horizontal portion 15a which is centrally apertured. Said latter portion may be used as a support if this is desired. A hub 17 is centrally secured in casing 12 having a portion extending through dial 10 and extending a short distance at the front thereof. A shaft 18 is journaled in hub 17 and has a hand 19 secured to its front end, which hand moves in front of and cooperates with dial 10. Hand 19 has a pointed end 19a, which end is adapted to cooperate with and to register with some one of a multiplicity of indications 10a formed on dial 10. As shown in Fig. 1 indications 10a are arranged in a circle and these may be given different colors as indicated in Fig. 1. These indications in practice have been painted on dial 10, which dial also has thereon a colored circle 10b and a colored border 10c extending along its sides and top. Said dial also has thereon a decoration in the form of a broken circle 10d having points 10e at its spaced ends.

Shaft 18 has secured to its rear end a toothed wheel 20. A lever 21 is pivotally connected between a pair of arms 22 which project from a magnet frame 23 having a horizontal base portion 23a which is secured by headed and nutted screws 24 to the horizontal shelf portion 25a of a bracket 25 which is in turn secured by rivets 26 to a supporting plate 27 extending vertically near the front of casing 12 and which carries hub 17. Plate 27 is supported by and secured to the front side of casing 12 by headed and nutted bolts 27a. Washers 27b which may be of resilient material surround said bolts between the wall of casing 12 and plate 27. While lever 21 could be connected to arms 22 in various ways, in the embodiment of the invention illustrated a headed and nutted bolt 28 extends through and between said arms on which are mounted spacers 29 at each side of lever 21. Lever 21 is fulcrumed on an

arm 23b extending from frame 23 by a headed and nutted bolt 30. A pawl 31 is pivotally connected to the lower end of lever 21 by the headed stud 32, said pawl having an arm adapted to engage a projection 21a at the lower end of lever 21, which projection acts as a stop. Pawl 31 is adapted to cooperate with tooth member 20. Shaft 18 carries at its rear end a disk-like portion 18a to which is secured by the headed screws 33 a bar 34. An arm 35 is swingingly mounted on a stud 36 secured adjacent the end of bar 34. Arm 35 has connected thereto or formed as a part thereof at its terminal portion a contact member or part 35a and in the embodiment of the invention illustrated, this part is shown as of angle shape, the angle approximating a right angle. A bar 37 is connected to the lower portion of plate 27 by a nutted stud 38 extending through said plate and through a spacing sleeve 39, a washer 40 being shown as engaging bar 37. Stud 38 extends through a slot 37a extending longitudinally and centrally of bar 37. Bar 37 will be made of insulating material and the same has secured to the sides thereof contact members 41 and 42. The end of bar 37 has an angular recess therein the studs of which are at substantially the same angle as the angle on swinging arm 35. Contact members 41 and 42 have their end portions bent to extend along the sides of said angular recess and said portions are spaced from each other. A tensile spring 43 is connected at one end to lever 21 above its fulcrumed point and at its other end to a pin 44 secured in plate 27. Conductors 45 and 46 are connected respectively to contacts 41 and 42. Conductor 45 extends to one terminal of a transformer 47 and a conductor 48 extends from the other terminal of transformer 47. Transformer 47 comprises a frame 47a secured to the lower part of casing 12 by headed and nutted bolts 47b. Washers 47c are inserted between said frame and said casing and may be of resilient material. A pair of conductors 49 are also connected to transformer 47 and will be connected to a plug adapted to be in turn connected to an electrical socket. Conductors 46 and 48 as well as conductors 49 are shown as extending through an insulating bushing 50 secured in the cylindrical wall of casing 12. Conductors 46 and 48 which may be in the form of a cord, are in turn secured to a signal 51 shown as in the form of a bell or gong and which may be of any suitable and standard construction.

Toothed wheel 20 will be made of iron or steel and a permanent magnet 52 has spaced poles 52a adapted to align with adjacent teeth on said wheel. Magnet 52 is carried by a headed stud 53 extending therethrough and through a spacing member 54 and secured in plate 27. A washer 55 is shown disposed under the head of screw 53.

Frame 23 carries a magnet 56, the core of which is connected to the arms 22. A pair of conductors 57 are connected to magnet 56 and to binding posts 58 on a member 59 of insulating material secured to plate 27. Conductors 60 are also connected respectively to binding post 58 and these extend through an insulating bushing 61 in the cylindrical wall of casing 12. A pair of conductors 62 and 63 are provided connected at one end, which connection is shown as covered by an insulating covering 64. Conductors 62 and 63 also extend through bushing 61. One conductor 60 and conductor 63 will have secured thereto a plug adapted to be connected to an electric socket for supplying current. A conductor 60 and conductor 62 will be connected to a switch

which will be closed for operating the device. This switch may be connected to the drawer of a cash register so that each time the register is operated the switch will be closed.

In operation, the plug connected to conductors 49 will be connected to an electric socket for supplying current. A conductor 60 and conductor 62 will be connected to the cash register as described. Each time the cash register is operated current will be supplied to magnet 56 by the closing of the switch to which conductors 60 and 62 are connected. When magnet 56 is operated arms 22 will be quickly drawn toward said magnet. This will swing lever 21 quickly and pawl 31 will engage the teeth on wheel 20 and a sudden rotative impulse will be given to this wheel. The switch closing the circuit will be only momentarily closed and magnet 56 will be at once deenergized. Lever 21 will be swung to its normal position by spring 43 and in this return movement pawl 31 will swing about its pivot 32 so that wheel 20 will not be affected. Wheel 20, shaft 18 and hand 19 rotate freely for several revolutions and finally come to rest. As wheel 20 comes to rest magnet 52 will stop said wheel with teeth thereon aligned with the poles 52a and hand 19 will then register with its pointer 19a registering centrally with one of the indications 10a. Bar 34 and arm 35 rotate with shaft 18 and when pointer 19 stops in vertical position registering with the triangular indication 10a arm 35 will come to rest in the angular end of bar 37 and the angular sides of arm 35 forming a contact member will bridge contacts 41 and 42 and close a circuit through the signal 51. Signal 51 will be operated. In practice, this signal has been a large gong which will produce a loud sound which can be heard all through the establishment. Everyone present will then realize that someone has gotten a free purchase or prize. Arm 35 will only connect contacts 41 and 42 when hand 19 comes to rest in vertical position. The circuit including contacts 41 and 42 will not be closed no matter how slowly arm 35 passes thereover. The circuit will only be closed when member 35 comes to rest in the position shown in Fig. 4. It will be understood that the position of hand 19 on shaft 18 can be varied so that anyone of the indications 10a could form the winning position.

From the above description it is seen that I have provided a simple, efficient and very entertaining form of signal or indicating device. The device when installed in a store, restaurant or tavern creates a great deal of interest and everyone watches the device to see if their purchase brings up the winning position. The signal adds greatly to the interest in the device. The device is attractive in appearance and in fact, forms a decoration for a bar, counter or other location. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A signal and indicating device having in combination, a dial having a multiplicity of circumferentially spaced indications thereof, a freely rotatable hand movable over said dial, means

for giving a rotating impulse to said hand, means for causing said hand to come to rest in registry with one of said indications, a freely rotatable shaft on which said hand is mounted, a swinging arm carried by said shaft, said arm having an angle shaped contact at its terminal portion, an electrically operated signal, a pair of spaced contacts disposed at an angle to each other, said angle being substantially the same as the angle on said arm, said angularly shaped contact being adapted to engage said last mentioned contacts and bridge the same for completing a circuit and operating said signal when said hand stops in registry with a certain one of said indications but to pass over said contacts without bridging them before said hand stops.

2. A signal and indicating device having in combination, a dial having a multiplicity of circumferentially spaced indications arranged in a circle thereon, a freely rotatable hand movable over said dial and constituting a pointer adapted to point to and align with said indications, means for giving a rotating impulse to said hand, means for causing said hand to come to rest in alignment with some one of said indications, a member connected to rotate with said hand, an arm mounted on said member and swingable thereon about an axis spaced from the axis about which said hand rotates, a contact carried by said arm, an electrically operated signal and a circuit for said signal adapted to be closed by said contact member for operating said signal when said hand stops in a certain position.

3. A signal and indicating device having in combination, a rotatable member such as a hand, means for giving said member a rotative impulse, a second member connected to rotate with said member, an arm mounted on said second member and swingable thereon about an axis spaced from

the axis about which said first mentioned member rotates, a swinging contact carried at the end of said arm, an electrically operated signal, a pair of spaced contacts adapted to be engaged and electrically connected by said first mentioned contact when said first mentioned member comes to rest in a certain definite position for closing the circuit through said signal and operating the same, said first mentioned contact being constructed and arranged to pass over said pair of contacts without electrically connecting them as said arm rotates.

4. A signal and indicating device having in combination, a dial having a multiplicity of circumferentially spaced indications thereon, a freely rotatable shaft arranged coaxially with said dial, a hand secured to said shaft movable over said dial, a toothed wheel secured to said shaft, a swinging lever at one side of said wheel, a pawl on said lever adapted to engage the teeth of said wheel, means for giving a sudden swinging impulse to said lever and pawl to cause said pawl to give a rotating impulse to said wheel, shaft and hand, an arm carried by said shaft, an angle-shaped contact swingably mounted on said arm, a pair of spaced contacts disposed at an angle to each other, said angle being substantially the same as the angle on said arm, said angularly shaped contact being adapted to engage said last mentioned contacts and electrically connect the same for completing a circuit when said hand stops in registry with a certain one of said indications but to pass over said spaced contacts without electrically connecting them in the rotation of said hand before the latter stops and an electrically operated signal operated when said circuit is closed.

ROBERT LADUE.
